UNITED STATES PATENT OFFICE.

JAMES WILLIAMS, OF PORTLAND, OREGON.

ROWLOCK FOR BOATS.

SPECIFICATION forming part of Letters Patent No. 449,787, dated April 7, 1891.

Application filed November 6, 1890. Serial No. 370,504. (No model.)

To all whom it may concern:

Be it known that I, JAMES WILLIAMS, of the city of Portland, county of Multnomah, and State of Oregon, have invented certain new and useful Improvements in Rowlocks for Boats; and I hereby declare the following specification and the drawings accompanying to be a full, clear, and exact description of the same.

10 My invention relates to the method of mounting rowlocks for boats on metal seats or supports; and it consists in providing two or more independent bearings at each side of the axis fore and aft; also, a spherical bearing 15 in the center, so as to secure a broader base, greater stability, and increased bearing and wearing surfaces, two of the bearings being segmental dovetail ledges and the third one spherical, as shown in the accompanying 20 drawings, in which—

Figure 1 is a vertical section taken longitudinally through the center of one of my improved rowlocks. Fig. 2 is a plan view of a complete rowlock. Fig. 3 is an end view of 25 the same, and Fig. 4 is a transverse section of Fig. 2 on the line *x y*.

Similar letters of reference on the different figures indicate corresponding parts.

The base-plate A, I form in one piece, with 30 a spherical pivot B in the center and two angular ledges C and D, the faces of all being swept from the center *a*, Figs. 1 and 2. This base-plate has extensions at each end to receive the fastening screws or bolts to attach 35 it to the gunwale E of a boat in the usual manner.

The throat or oar-support F, I form with corresponding ledges to fit loosely at C and D into the base A; also, with a concave socket 40 to fit loosely over the spherical projection B. So this throat-piece F is free to turn about its axis with the motion of the oar, but held at the same time firmly in its seat on the base-plate A.

45 The distance from D to D, Fig. 2, is made longer than the width of the throat-piece F, so that when the latter is turned at a right angle to the base-plate A it can be taken off or put on instantly; or if the oar comes in 50 contact with anything not seen by the rower, as soon as the oar swings fore and aft and the rowlock comes to a right angle the oars and throat-piece will fall inboard and leave the gunwale free from obstruction, or the row-

lock will unship by swinging the oar fore and aft until the throat-piece comes at a right angle to the sole-plate A.

In this construction of rowlocks the strain of the oar in rowing either forward or backward falls on three of the ledges C and D and 60 also on the spherical bearing B in the center, and being thus distributed over a large area there is little friction or wear to cause lost motion, which is common in rowlocks now in use.

65 The spherical bearing B can be omitted altogether, or a simple pin in the center can be substituted, without interfering with the action or objects of the double dovetail ledges C and D, which independently form a large 70 bearing and wearing surface. The objects of the spherical form are to provide a maximum amount of wearing-surface and at the same time permit the throat-piece F to roll or turn 75 out of its seat by side-thrust alone when standing transverse to the sole-plate A.

Having thus described the nature and objects of my invention, also the manner of constructing and applying the same, what I claim as new, and desire to secure by Letters 80 Patent, is—

1. In a rowlock for boats, the combination of the base-plate A, provided with a spherical pivot B in the center and two angular ledges C and D, the throat or oar-support F, provided with corresponding ledges to fit closely at C and D, and also with a concave socket to fit loosely over the spherical projection B, so that said throat itself may be free to turn about its axis with the motion of the oar. 90

2. In a rowlock for boats, the combination of the base-plate A, having the spherical pivot B at the center and the two ledges C and D, said base-plate having also extensions at each end to receive suitable fastenings whereby it 95 is attached to the gunwale, the throat or oar-support F, formed with corresponding ledges to fit closely at C and D into the base A, and also with a concave socket to fit loosely over the spherical projection B, all arranged to 100 operate substantially as described.

In testimony whereof I have hereunto affixed my signature in the presence of two witnesses.

JAMES WILLIAMS.
